UNITED STATES PATENT OFFICE.

THOMAS WILLNER JOHNSON, OF DENVER, COLORADO.

CUSPIDOR.

1,397,636.

Specification of Letters Patent. Patented Nov. 22, 1921.

Application filed November 20, 1920. Serial No. 425,414.

To all whom it may concern:

Be it known that I, THOMAS WILLNER JOHNSON, a citizen of the United States, residing at Denver, in the county of Denver and State of Colorado, have invented a new and useful Cuspidor, of which the following is a specification.

This invention relates to cuspidors, one of its objects being to provide a sanitary device of this character which is self flushing and the parts of which are easily accessible.

A further object is to provide a structure utilizing a basket which can be flushed both inside and outside, the flushing operation being controlled by a float operated lever.

With the foregoing and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawing, which is a section through the device, the preferred form of the invention has been shown.

Referring to the drawing by characters of reference 1 designates a bowl-like body of porcelain or similar material mounted on legs 2 or in any other manner desired, this body being provided at the bottom with a drain pipe 3 while formed in the lower portion of the contracted mouth 4 of the body is an annular shoulder 5. Formed within the wall of the body and within the shouldered portion is an annular passage 6 having outlet openings 7 extending from the upper portion thereof and downwardly above the shoulder 5 while formed in the bottom wall of the annular passage 6 are concentric series of openings 8 extending downwardly and inwardly as shown.

The shoulder 5 is adapted to be engaged by the flanged upper end 9 of a basket 10 which is seated in the body and has supporting legs 11 designed to rest on the bottom portion of the body. The bottom of the basket is preferably extended upwardly, as indicated at 12, all portions of the basket being made of wire fabric.

A supply pipe 13 opens into the bottom wall of the passage 6 and is adapted to be

connected to a curved pipe. This pipe 13 has a valve 14 the stem of which is provided with an arm 15. Said arm extends partly around the basket 10 and is provided at its free end with a float 16 which also constitutes a weight for holding the valve normally opened.

When the float 16 is in its lowermost position, as shown in the drawing, water will flow from the pipe 13 and through the passage 6 to the various outlet openings 7 and 8, thus discharging in jets into and against the basket. The jets issuing from the openings 7 will be projected into the top portion of the basket while the jets issuing from the openings 8 will be directed against the outer surface of the basket. These jets will obviously flush the basket and clean it and as the water will enter the body 1 too rapidly to be carried off by the pipe 3, float 16 will arise and ultimately cut off the supply of water to the passage 6, thereby preventing the water from overflowing.

A device of this character is obviously kept clean and as it is formed of but few parts, it will not readily get out of order.

What is claimed is:

1. The combination with a body having an outlet opening in the bottom thereof, of an annular shoulder within the upper portion of the body, a basket supported in the body and having an open upper end engaging the shoulder, an annular passage within the wall of the body and adjacent the shoulder, said passage having outlet openings for directing jets of fluid downwardly into the open end of the basket and additional outlet openings for directing jets of fluid downwardly onto the outer surface of the basket, and means for directing liquid into the passage.

2. The combination with a body having an outlet opening in the bottom thereof, of an interior annular shoulder upon the wall of the body adjacent the top thereof, a basket having an open upper end engaging and supported by the shoulder, legs upon the bottom of the basket and engaging the body, an annular passage within the wall of the body and adjacent the shoulder, there being outlet openings extending from said passage for directing jets of liquid downwardly into the basket and additional outlet openings extending through a wall of the passage for

directing concentric series of jets downwardly against the outer surface of the basket, means for supplying liquid to the passage, a valve for controlling the flow of liquid through said means, and a combined float and weight for controlling the actuation of the valve.

In testimony that I claim the foregoing as my own, I have hereto affixed my signature in the presence of two witnesses.

THOMAS WILLNER JOHNSON.

Witnesses:
